BOTTLE WARMER

Arne B. Johnson, Madison, Wis.

Application April 15, 1952, Serial No. 282,320

8 Claims. (Cl. 219—40)

1

The present invention relates to liquid conductor heater structures, and more particularly to a container having a removable liquid heater adapted for use in warming nursing bottles or the like.

Liquid conductor heaters generally comprise a liquid container of insulating material having conducting electrodes in a portion thereof arranged to be immersed in the contained liquid. A suitable electric current is applied to opposing pairs of the conductive electrodes to cause the electric current to be conducted from one electrode to the other through the conductive path established by the contained liquid. The resistance of the conductive path causes the temperature of the contained liquid to rise to a desired amount depending upon the variable factors such as the applied potential, the area and spacing of the electrodes, and the amount and kind of contained liquid.

When using a liquid conductor heater structure as a nursing bottle warmer, the contained liquid is usually tap water. Tap water generally has a number of dissolved salts therein which, in the operation of the liquid conductor heater, become deposited on the heater electrodes. The accumulation of deposited salts on the heater electrodes gradually forms an insulating coating which impairs the efficiency of the heater structure and reduces the current flow through the conductive liquid to a value where insufficient heating action is obtained. It is therefore necessary to periodically replace or clean the electrode structures.

It is an object of the present invention to provide an improved liquid conductor heater structure in which all of the conductive electrodes may be easily removed as a unit for cleaning or replacement.

Another object of the invention is to provide a simplified assembly of removable conductive electrodes for use in a liquid conductor heater structure.

Yet another object of the invention is to provide an improved arrangement for automatically connecting a removably secured electrode structure to the fixed electric power supply terminals of a liquid conductor heater container when the electrode structure is secured thereto.

A feature of the invention is the provision of a liquid heater including a liquid container of insulating material and a false bottom assembly of insulating material adapted to be removably secured within the liquid container in a position overlying the bottom thereof, the false bottom

2

assembly including a pair of planar electrodes positioned generally parallel to the plane of the false bottom and spaced from each other.

Another feature of the invention is the arrangement of a pair of planar electrodes on the above-mentioned false bottom structure with the lower electrode arranged to expose a portion of the upper electrode to which an electrical connection may be extended past the lower electrode.

Yet another feature of the invention is the provision of a pair of resilient portions for automatically establishing electrical connections between respective ones of a pair of electrodes carried by a removable false bottom structure and respective ones of a pair of fixed electric terminals on the inner bottom surface of a liquid conductor container in a manner to assure positive electrical connections.

20 A further feature of the invention is the novel arrangement for securing a conductive planar electrode to an insulating false bottom structure by means of an integral punched projection of the planar electrode, the projection being suitably retained in the body of the false bottom structure.

Further objects, features and the attending advantages of the invention will be apparent from the following specification and drawings in which:

25 Fig. 1 is an elevation view of the liquid conductor heater with a bottle in position to be warmed;

Fig. 2 is a top plan view;

Fig. 3 is a detail plan view of the underside of the removable false bottom and electrode structure;

Fig. 4 is a bottom view of the liquid container;

Fig. 5 is an exploded perspective view to show the assembly of the removable false bottom and liquid container;

Fig. 6 is an enlarged fragmentary cross section on line 6—6 of Fig. 2; and

30 Figs. 7, 8 and 9 are fragmentary details of modified forms of the invention.

35 In practicing the invention, a liquid container of insulating material is provided with a pair of spaced electric power terminals on its inside bottom surface. A perforated false bottom of insulating material is adapted to be removably secured on the inside bottom surface of the container. A pair of planar conductive electrodes having perforations therethrough are secured to the underside of the false bottom to extend in a plane generally parallel to the false bottom in

spaced positions with respect to each other. The lower electrode is arranged to expose a surface of the upper electrode to which an electrical connection may be extended past the lower electrode from the bottom surface of the container. The electrical connections are established by resilient connectors such as coil springs or depending projections of each electrode. The perforations in the false bottom and planar electrodes enable the contained liquid to circulate between the electrodes for conducting an electric current therebetween. To assure the registry of the connections between the electrodes and terminals when the false bottom is assembled in the container, a plurality of projections are provided on the inner bottom surface of the container and they are adapted to be received in the plurality of peripheral indentations of the false bottom thus determining the angular position of the false bottom with respect to the bottom of the container and the electric terminals. In one form of the invention each of the planar electrodes is secured to the false bottom by upwardly extending integral projections that are embedded or otherwise secured to the body of the false bottom.

For a more detailed description of the invention reference is made to Figs. 1 through 6 of the drawings. The liquid container 10 is formed of porcelain or other insulating material and is provided with a recessed portion 11 on the underside of the bottom thereof. An electric line cord 12 is passed through the opening 13 in the sidewall of the container into the bottom recessed portion 11 and respective conductors thereof are connected to the electric terminals 14 and 15. Terminals 14 and 15 are provided with upper contact surfaces 16 and 17, respectively, which are received in suitable apertures on the upper side of the bottom portion of the container. A removable false bottom assembly generally shown at 19 is arranged to be secured on the upper surface of the bottom portion of the container by means of the bolt 20 which may be threaded into the bushing 21 that is secured by the bolt 22 to the bottom surface of the container.

As more clearly shown in Figs. 2 and 5 of the drawings, the removable false bottom 19, which is formed of insulating material similar to the material of the container 10, is provided with a plurality of perforations 24 therethrough. A plurality of raised surfaces 25 are also provided and a nursing bottle such as shown at 26 (Fig. 1) may be rested thereon for purposes of warming the bottle. The raised surfaces 25 serve to permit the circulation of water beneath the bottle and into the perforations 24 to a central indentation 27 of the false bottom (Fig. 6).

As more clearly shown in Figs. 3 and 6 of the drawing the underside of the false bottom 19 has secured thereto a pair of planar electrodes 30 and 31 formed of conductive material, such as stainless steel or the like. The electrodes are positioned in planes generally parallel to the plane of the false bottom and spaced from each other across the central indentation 27. The lower conductive electrode 31 is shaped and positioned in relation to the upper electrode 30 in a manner to expose a portion 32 of the upper electrode. The bottom surface of the container includes a projection 47 which extends upwardly past the electrode 31. The projection 47 has an opening therein in which the coil spring 33 is positioned to make electrical connection between

the electric terminal 16 and the portion 32 of the electrode 30 when the removable false bottom 19 is secured to the upper bottom surface of the container 10. A similar coil spring 34 is effective to establish connection with a portion 35 of the lower electrode 31. In such manner, electric power from the line cord 12 is applied across the opposing surfaces of the conducting electrodes 30 and 31. It will be noted that each of the conductive electrodes is provided with a plurality of perforations such as shown at 36, through which liquid may circulate when the container is filled with a suitable liquid such as tap water or the like. It should be apparent that when the line cord 12 is connected to a source of suitable electric power, an electric current will be conducted through the liquid between the electrodes 30 and 31 to thereby heat the liquid due to the resistance of the conductive path therein.

As shown in Fig. 6, each of the planar electrodes 30 and 31 are supported in a plane generally parallel to the plane of the false bottom 19 by means of integral punched up-standing projections 29 and 37 which are folded over at 38 and 39 in suitable recesses on the upper side of the false bottom 19. A waterproof heat resistant and electrically insulating cement such as shown at 40 and 41 completes the assembly of the planar electrodes 30 and 31 to the false bottom 19.

In order to assure the correct registry of the exposed terminal portions 32, 35 of the electrodes 30, 31, respectively, with the coil springs 33, 34 and electric terminals 16, 17, the false bottom 19 is provided with a plurality of peripheral indentations 42-44. Suitable upwardly extending projections 45-47 are arranged on the upper bottom surface of the container to be received in the recesses 42-44 and thereby locate the angular position of the false bottom 19 when secured within the container.

A modified form of the invention is shown in Fig. 7 wherein the planar electrodes 30 and 31 are secured to the false bottom 19 by means of rivets 50 and 51. The electrode 30 is provided with an integral downwardly extending projection 52 for establishing contact with the electric terminal 16 and, similarly, the electrode 31 is provided with an integral downwardly extending projection 53 for establishing contact with the electric terminal 17 when the false bottom 19 is secured within the container.

Fig. 8 shows another modification of the invention in which the planar electrodes 30 and 31 are secured to the false bottom 19 by means of the rivets 50 and 51. In this embodiment the coil springs 33, 34 are provided for establishing electrical connections to the respective electric terminals 16, 17.

In the embodiment shown in Fig. 9 the planar electrodes 30, 31 are secured to the false bottom 19 by integral upstanding projections 29, 37 in a similar manner to that previously described in Fig. 6 of the drawings. In this arrangement, however, the electrode 30 is provided with the integral downwardly extending projection 52 and the electrode 31 is provided with the integral downwardly extending projection 53 for establishing electrical contact with the electric terminals 16 and 17, respectively.

It will be apparent that the liquid conductor heater in accordance with the invention includes a removable heater unit which is of simple construction and which may be easily replaced. The

construction is such that unskilled persons can replace the unit correctly so that the heater will operate properly.

It should be understood that various other modifications may be made within the spirit of the invention and the scope of the appended claims.

I claim:

1. In a liquid conductor heater of the type having a liquid container of insulating material and a pair of electric terminals in the base portion thereof connected to a line cord for connection with a source of electric current, the removable electrode assembly including in combination, a perforated false bottom of insulating material, a pair of planar electrodes of conductive material secured to said false bottom in spaced relation to each other and in planes generally parallel to the plane of the false bottom, said false bottom and said electrodes forming a unitary assembly for easy replacement thereof, the lower one of said electrodes being arranged to expose a surface of the upper one of said electrodes, means independent of said terminals for removably securing said unitary assembly in said container, and resilient conducting means electrically interconnecting a respective one of said terminals with a respective one of said electrodes when said false bottom is secured within said container, one of said conducting means extending past the lower of said electrodes into electrical contact with the exposed surface of the upper of said electrodes.

2. In a liquid conductor heater of the type having a liquid container of insulating material and a pair of electric terminals in the base portion thereof connected to a line cord for connection with a source of electric current, the removable electrode assembly including in combination, a perforated false bottom of insulating material, a pair of planar electrodes of conductive material, each of said electrodes having an integral projection secured to said false bottom to mount said electrodes therefrom in spaced relation to each other and in planes generally parallel to the plane of the false bottom, so that said false bottom and said electrodes form a unitary replaceable assembly, the lower one of said electrodes being arranged to expose a surface of the upper one of said electrodes, spring means electrically interconnecting a respective one of said terminals with a respective one of said electrodes when said false bottom is secured within said container, one of said spring means extending past the lower of said electrodes into electrical contact with the exposed surface of the upper of said electrodes, and means independent of said spring means for securing said assembly to said base portion.

3. In a liquid conductor heater of the type having a liquid container of insulating material and a pair of electric terminals in the base portion thereof connected to a line cord for connection with a source of electric current, the removable electrode assembly including in combination, a perforated false bottom of insulating material, a pair of planar electrodes of conductive material, each of said electrodes having an integral projection secured to said false bottom to mount said electrodes therefrom in spaced relation to each other in planes generally parallel to the plane of the false bottom, so that said false bottom and said electrodes form a unitary assembly, the lower one of said electrodes being arranged to expose a surface of the upper one of said electrodes, each of said electrodes having

an integral downwardly extending projection for electrically interconnecting said electrode with a respective one of said terminals when said false bottom is secured within said container, said downwardly extending projection of said upper electrode extending past said lower electrode to establish contact with one of said terminals, and means independent of said terminals for securing said electrode assembly to said base portion.

10 4. In a liquid conductor heater of the type having a liquid container of insulating material and a pair of electric terminals in the base portion thereof connected to a line cord for connection with a source of electric current, the removable electrode assembly including in combination, a removable perforated false bottom of insulating material, means to removably secure said false bottom within said container to the base portion thereof, a pair of planar electrodes of conductive material secured to said false bottom in spaced relation to each other in planes generally parallel to the plane of the false bottom, the lower end of said electrodes being arranged to expose a surface of the upper one of said electrodes, and a pair of coil springs for electrically interconnecting a respective one of said terminals with a respective one of said electrodes when said false bottom is secured within said container, one of said coil springs extending past the lower of said electrodes to establish electrical contact between the exposed surface of the upper of said electrodes and one of said terminals.

35 5. A liquid conductor heater including in combination, a liquid container of insulating material having a base portion with a pair of electric terminals secured therein adapted to be connected to a line cord for connection with a source of electric current, said container having a wall portion integral with said base portion, a removable electrode assembly including a perforated false bottom of insulating material, a pair of planar electrodes of conductive material, and means for securing said electrodes to said false bottom with said electrodes in spaced relation to each other and in planes generally parallel to the plane of the false bottom, so that said false bottom and said electrodes form a unitary replaceable assembly, resilient conductor means for electrically interconnecting a respective one of said terminals with a respective one of said electrodes when said false bottom is secured within said container on said base portion thereof, the lower one of said electrodes being arranged to expose a surface of the upper one of said electrodes, one of said conductor means extending past the lower of said electrodes and making electrical contact with the exposed surface of the upper of said electrodes, and means independent of said terminals for securing said electrode assembly to said base portion.

60 6. A liquid conductor heater including in combination, a liquid container of insulating material having a base portion with a pair of electric terminals and a mounting stud secured therein, said terminals being adapted to be connected to a line cord for connection with a source of electric current, said container having a wall portion integral with said base portion, a removable electrode assembly including a perforated false bottom of insulating material and a pair of planar electrodes of conductive material, each of said electrodes having an integral projection secured to said false bottom to mount said electrodes therefrom in spaced relation to each other

and in planes generally parallel to the plane of the false bottom so that said false bottom and said electrodes form a unitary replaceable assembly, resilient conductor means for electrically interconnecting a respective one of said terminals with a respective one of said electrodes when said false bottom is secured within said container on said base portion thereof, the lower one of said electrodes being arranged to expose a surface of the upper one of said electrodes, one of said conductor means extending past the lower of said electrodes and making electrical contact with the exposed surface of the upper of said electrodes, and mounting means cooperating with said mounting stud in said base portion for securing said electrode assembly to said base portion.

7. A liquid conductor heater including in combination, a liquid container of insulating material having a base portion with a pair of electric terminals secured therein adapted to be connected to a line cord for connection with a source of electric current, said base portion having at least one upwardly extending projection thereon within the container, a removable electrode assembly including a perforated false bottom of insulating material, said false bottom having a central indentation and at least one other indentation on the underside thereof adapted to fit about said projection on said base portion and thereby locate the angular position of the false bottom thereon, said assembly including a pair of perforated planar electrodes of conductive material secured to said false bottom in spaced relation to each other in planes generally parallel to the plane of the false bottom and extending across said central indentation, the lower one of said electrodes being arranged to expose a surface of the upper one of said electrodes, means independent of said terminals for securing said electrode assembly to said base portion, and resilient conductor means for electrically interconnecting a respective one of said terminals with a respective one of said electrodes when said false bottom is secured within said container, one of said conductor means extending past the lower of said electrodes and making electrical contact with the exposed surface of the upper of said electrodes.

8. A liquid conductor heater including in combination, a liquid container of insulating material having a base portion with a pair of electric terminals at the sides thereof and a central mounting stud secured thereto, said electric terminals

5 being adapted to be connected to a line cord for connection with a source of electric current, said base portion having an upwardly extending tubular projection about one of said terminals and having recesses therein above each of said terminals, a removable electrode assembly including a perforated false bottom of insulating material, said false bottom having a central indentation on the underside thereof and a notch at the edge 10 thereof adapted to fit about said projection on said base portion and thereby locate the angular position of the false bottom thereon, said assembly including a pair of perforated planar electrodes of conductive material secured to said false bottom in spaced relation to each other in planes generally parallel to the plane of the false bottom and extending across said central indentation, each of said electrodes including an integral projection thereon for securing the same to said false bottom, the lower one of said electrodes having a notch aligned with said notch in said false bottom to expose a surface of the upper one of said electrodes, mounting means cooperating with said mounting stud for securing said electrode assembly to said base portion, and coil springs in said recesses for electrically interconnecting a respective one of said terminals with a respective one of said electrodes when said false bottom is secured within said container, one of said coil springs extending through said tubular projection past the lower of said electrodes into electrical contact with the exposed surface of the upper of said electrodes.
